UNITED STATES PATENT OFFICE

135,305

DESIGN FOR A PIN

Frank H. Bercker, Milwaukee, Wis., assignor to Army Air Cadettes, Milwaukee, Wis., a corporation of Wisconsin

Application November 6, 1942, Serial No. 108,714

Term of patent 7 years

To all whom it may concern:

Be it known that I, Frank H. Bercker, a citizen of the United States, residing at Milwaukee, in the county of Milwaukee and State of Wisconsin, have invented a new, original and ornamental Design for a Pin, of which the following is a specification, reference being had to the accompanying drawing, forming part thereof.

Figure 1 is a plan view of a pin showing my new design; and

I claim:

The ornamental design for a pin, as shown.

FRANK H. BERCKER.
